(57) **CLAIM**

The ornamental design for a bin for refrigerator, as shown and described.

DESCRIPTION

FIG. 1 is a front perspective view of a bin for refrigerator, showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is an exploded view thereof;

FIG. 9 is a perspective view thereof showing the bin for refrigerator in a refrigerator door environment;

FIG. 10 is an enlarged view of the encircled portion 9 in FIG. 1;

FIG. 11 is an enlarged view of the encircled portion 10 in FIG. 1; and,

FIG. 12 is an enlarged view of the encircled portion 11 in FIG. 6.

The evenly dashed broken lines in the figures depict environmental subject matter and form no part of the claimed design. The dot-dash broken lines encircling portions of the claimed design that are illustrated in enlargements form no part of the claimed design. The bracket shown in FIG. 8 indicates an association of components and forms no part of the claimed design.
